UNITED STATES PATENT OFFICE

WALTON B. ROBE, OF TOWSON, MARYLAND, ASSIGNOR TO GEORGE S. SLOAN AS TRUSTEE
FOR EGAL METAL PRODUCTS COMPANY, OF BALTIMORE, MARYLAND, BANKRUPT

GAUGE FOR POSITIONING CHILLS OR CORES ON SAND MOLDS

Application filed November 19, 1928. Serial No. 320,454.

My invention relates to improvements in gauges for positioning chills or cores on sand molds.

The object of my invention is to provide a gauge adapted to cooperate with the guide pins of the drag of a sand mold, whereby the chills may be accurately and quickly positioned in the supports in the drag, in respect to the ends and sides of the drag.

Another object of my invention is to provide a gauge of this character which is readily placed over the guide pins of the drag now used for guiding the cope thereon, so that it will at all times assume a very accurate position in respect to the sides and ends of the drag, so that the chills and sand core are properly positioned on the drag.

A further object of my invention is to provide a simple, cheap and effective gauge of this character having certain details of structure and combination of parts hereinafter more fully described.

In the accompanying drawings:—

Figure 1 is a top plan view of a drag showing my improved gauge applied thereto showing four chills properly positioned thereon by my improved gauge.

Figure 2 is a top plan view similar to Figure 1 showing the sand core properly positioned thereon by another form of gauge.

Figure 3 is a vertical sectional view of a drag showing the chills and sand core properly positioned thereon by the gauge, and the cope in position thereon.

In the manufacture of cylinder heads or other castings where chills and sand cores are used it has consumed considerable time to accurately position the chills and sand cores on the drag in their proper position in respect to each other and to the sides and ends of the drag, but by my improved gauge it is a very simple matter to properly and rapidly position the chills and sand cores on the drag in respect to each other, and to the sides and ends of the drag.

Referring now to the drawings, 1 represents any ordinary drag, which is provided with the usual guide pins 2 and 3 at its ends which cooperate with the eyes carried by the cope, all of which is well understood and

needs no further description. My improved gauge consists of an elongated bar 4, of a length slightly greater than the length of the drag and is provided at each end with the laterally turned ends 5 and 6, the inner faces of which are provided with the vertically disposed V shaped notches 7 and 8 corresponding with the outer faces of the guide pins 2 and 3 carried by the drag 1. The elongated bar 4, at proper intervals, is provided with outwardly extending lugs 9, 10, 11 and 12, adapted to serve as stops and means for proper positioning of the four chills 13, 14, 15 and 16 in their proper position upon the supports carried by the drag, such as shown in my copending application filed July 6, 1928, Serial No. 290,822, and thus it will be seen that the chills are rapidly and accurately positioned upon the chill supports carried by the drag.

In Figure 2, I have shown the same principle involved in which the bar 4 has a single projection or lug 17 which is adapted to position the sand core 18 on the drag. In the use of this gauge it will be understood that the chills are first placed on the chill supports in approximately their proper position, and the gauge is lowered down over the guide pins 2 and 3 of the drag until it rests firmly upon the upper end walls of the drag the same as the form shown in Figure 1. A soft tool is used to tap the chills up against the lugs 9, 10, 11 and 12, and when in contact with the said lugs the chills are in their proper position over the chill supports. When using my improved gauge for positioning the sand core the gauge is first lowered over the guide pins of the drag and the core 18 is then placed in position with one side wall engaging the bar 4, and one end engaging the lug or projection 17, whereby the core is properly placed in position in respect to the chills and also in respect to the sides and ends of the drag.

The bar 4 in Figures 2 and 3 is provided with downwardly extending lugs 19 which rest upon the ends 20 and 21 of the drag 1, whereby the gauge is supported above the drag so that it will engage the sand core 18.

which is supported above the upper face of the drag as shown in Figure 3.

Having thus fully described my invention what I claim is:—

- 5 1. A gauge adapted to cooperate with the guide pins of a mold drag, and having means for determining the position of the chills on the drag.
- 10 2. A gauge adapted to slide over the guide pins of a mold drag and having stops adapted to determine the position of the chills on the drag.
- 15 3. A gauge adapted to cooperate with the drag, and having means for determining the position of the chills on the drag.
- 20 4. A gauge of the character described comprising an elongated member having laterally turned ends adapted to cooperate with the guide pins of the drag, and having means for determining the proper position of the chills on the drag.
- 25 5. A gauge of the character described comprising an elongated member having laterally turned ends having vertically disposed grooves adapted to cooperate with the outer faces of the guide pins of the drag, and having means for determining the proper position of the chill on the drag.
- 30 6. A gauge of the character described comprising an elongated flat bar having laterally turned ends adapted to extend inwardly beyond the guide pins of the drag, and having vertically disposed grooves adapted to receive the outer faces of the guide pins, and means carried by said bar and extending inwardly to form stops for determining the proper position of the chills on the drag.

In testimony whereof, I have signed this specification.

WALTEN B. ROBE.
